The ornamental design for a modular retaining wall block, as shown and described.

DESCRIPTION

FIG. 1 is a perspective view of a masonry block used in a retaining wall of our new design;

FIG. 2 is a top plan view thereof;

FIG. 3 is a front elevational view thereof;

FIG. 4 is a side elevational view thereof, as taken from the left in FIGS. 1-3 (the right side is a mirror image of the left side);

FIG. 5 is a rear elevational view thereof;

FIG. 6 is a bottom plan view thereof;

FIG. 7 is a perspective view of a second masonry block used in a retaining wall of our new design;

FIG. 8 is a top plan view thereof;

FIG. 9 is a front elevational view thereof;

FIG. 10 is a side elevational view thereof, as taken from the left in FIGS. 7-9 (the right side is a mirror image of the left side);

FIG. 11 is a rear elevational view thereof; and,

FIG. 12 is a bottom plan view thereof.
